HEATING AND VENTILATING UNIT

John W. McElgin, Philadelphia, Pa., assignor to John J. Nesbitt, Inc., Holmesburg, Pa., a corporation of Pennsylvania

Application March 2, 1953, Serial No. 23,844

Term of patent 14 years

(Cl. D62—4)

Figure 1 is a perspective view taken from one end of a heating and ventilating unit embodying my new design;

Figure 2 is a perspective view taken from the other end thereof.

I claim:

The ornamental design for a heating and ventilating unit, substantially as shown.
